(57) CLAIM

The ornamental design for a vehicle kitchen as shown and described.

DESCRIPTION

FIG. 1 is a front, left perspective view of a vehicle kitchen, according to an embodiment;

FIG. 2 is a front elevation view of the vehicle kitchen of FIG. 1;

FIG. 3 is a rear elevation view of the vehicle kitchen of FIG. 1;

FIG. 4 is a left side elevation view of the vehicle kitchen of FIG. 1;

FIG. 5 is a right side elevation view of the vehicle kitchen of FIG. 1;

FIG. 6 is a top plan view of the vehicle kitchen of FIG. 1; and,

FIG. 7 is a bottom plan view of the vehicle kitchen of FIG. 1.

The ornamental design which is claimed is shown in solid line. The broken lines of equal length dashes in the drawings are for the purpose of illustrating portions of the vehicle kitchen and form no part of the claimed design. Broken lines formed by unequal length dashes (i.e., dash-dot) define bounds of the claimed design.
